UNITED STATES PATENT OFFICE.

BENJAMIN F. SPARLING, OF UNIONVILLE, NEW YORK.

SAFETY DEVICE FOR LOADING ELEVATORS.

Application filed March 2, 1922. Serial No. 540,642.

To all whom it may concern:

Be it known that I, BENJAMIN F. SPARLING, a citizen of the United States, residing at Unionville, in the county of Orange 5 and State of New York, have invented certain new and useful Improvements in Safety Devices for Loading Elevators; and I do hereby declare the following to be a full, clear, and exact description of the invention, such as will enable others skilled in the art to which it appertains to make and use the same.

This invention relates to improvements in elevators of that type in which the starting 15 and stopping mechanisms are controlled by a pull rope, and one of its objects is the provision of novel means by which the pull rope may be locked against movement with relation to the car whereby to prevent the car 20 from being set in motion from one floor during the loading of the car at another floor.

A further object of the invention is the provision of a pull rope lock which shall be 25 simple, durable and efficient, which may be readily and quickly applied to any well known form of elevator car, and which may be readily and quickly operated to lock or release the pull rope.

With the above and other objects in view, the invention consists in the construction, combination and arrangement of parts hereinafter fully described and claimed, and 30 illustrated in the accompanying drawing,

35 wherein:

Figure 1 is a view in side elevation of a pull rope lock constructed in accordance with my invention, and

Figure 2 is a top plan view of the pull 40 rope lock, portions of the lock being in horizontal section.

Referring to the drawing by reference numerals, 1 designates one of the corner posts or timbers of an elevator car, and 45 2 the pull rope.

The pull rope lock comprises a bracket arm 3 which is secured to the corner post or timber 1 by bolts 4 and which extends from the corner post or timber in the direction of the pull rope 2. The outer end of 50 the bracket arm 3 is provided with a loop 5 through which the pull rope 2 passes. The loop 5 is of U-shape formation, and to provide it one end of the bracket arm 3 is 55 reversely bent. A rope gripping clutch or jaw 6 is pivotally and slidably connected to

and between the sides of the loop 5 through the medium of a bolt 7 which passes through the clutch or jaw 6 and through elongated openings 8 in the sides of the loop 5. The forward or active end 9 of the clutch or jaw 6 is concave and the pull rope 2 is adapted to be clamped between the active end 9 and the bight portion 10 of the loop 5. The clutch or jaw 6 is provided with an angular shank 11 which extends rearwardly therefrom and which is connected to the shorter arm 12 of an angle lever 13 by means of a pivot 14. The lever 13 has its short arm 12 pivoted to the bracket arm 3 by means of a rivet 15. The long arm 16 of the lever 13 extends upwardly, and is provided at its upper end with a weight 17 which is secured thereto by nuts 18.

The parts are so constructed and arranged 75 that, when the arm 16 of the lever 13 is swung into a position forwardly beyond the vertical axis of the pivot 15, the clutch or jaw 6 is moved into and held in inactive position, and such that when the arm 16 is 80 swung into a position rearwardly beyond the vertical axis of the pivot 15, the clutch or jaw 6 is moved into and held in active position. When the clutch jaw 6 is in inactive 85 position, the pull rope 2 may be freely operated, and when the clutch or jaw 6 is in active position the pull rope is clamped between it and the bight portion 10 of the loop 5 and held against movement with relation to the elevator car. The clutch or jaw 6 90 is limited in its rearward movement by the bolt 7 engaging the rear end walls of the slots 8, and in view thereof the lever 13 is limited in its forward and downward movement. To limit the downward and rearward 95 movement of the lever 13, a pin 19 is carried by the sides of the loop 5 for engagement by the shank 11 of the clutch or jaw 6 when the lever is in position to hold the clutch or jaw 100 6 in rope clamping or active position.

In practice, the pull rope 2 is locked when the elevator is stopped at a floor so that the rope may not be moved with relation to the elevator car from another floor during the loading of the car. When it is desired to start the elevator car, the pull rope is released. To lock the pull rope, it is only necessary to swing the lever 13 rearwardly beyond the vertical axis of the pivot 15, and to release the pull rope it is only necessary 105 to swing the lever 13 forwardly beyond the vertical axis of the pivot 15. The lock may 110

be readily and quickly operated and it prevents those accidents which are the result of the starting of an elevator far from a floor above or below that floor at which the car is being loaded.

While I have shown and described the preferred embodiment of my invention, it will be understood that minor changes in the construction, combination and arrangement of parts may be made without departing from the spirit and scope of the invention as defined by the claims.

Having thus fully described my invention, what I claim as new and desire to secure by Letters Patent, is:

1. An elevator pull rope lock comprising a bracket arm provided with a loop at one end through which the pull rope passes, a clutch or jaw pivotally and slidably connected to and between the sides of the loop, an angle lever pivoted to the bracket arm and having pivotal connection with the clutch or jaw, and a weight carried by said lever.
2. An elevator pull rope lock comprising a bracket arm provided with a relatively stationary jaw, a relatively movable jaw pivotally and slidably connected to the bracket arm, a lever by which the relatively movable jaw may be moved into and held in either its inactive or active position, and means for limiting the pivotal movement

of the relatively movable jaw in one direction.

3. An elevator pull rope lock comprising a bracket arm provided with a relatively stationary jaw, a relatively movable jaw pivotally and slidably connected to the bracket arm, an angle lever pivoted to the bracket arm and having pivotal connection with the relatively movable jaw, and a weight carried by said lever.

4. An elevator pull rope lock comprising a bracket arm carrying a relatively stationary jaw, a relatively movable jaw pivotally and slidably connected to the bracket arm, a lever having angularly disposed portions, said lever having one of its angularly related portions pivoted to said bracket, the point of pivoting of said lever being intermediate the ends of said portion, the free extremity of said portion pivoted to an end of said movable jaw, and said lever adapted to have its free extremity moved from one side to the other of the vertical axis of the pivot point of the lever to move and hold the movable jaw into either active or inactive position.

In testimony whereof I affix my signature in presence of two witnesses.

BENJAMIN F. SPARLING.
